UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

PLATE-CLAMPING DEVICE.

Application filed October 19, 1925. Serial No. 63,518.

This invention relates to rotary printing presses and has particular reference to the means for fastening stereotype plates or like printing surfaces to the peripheries of the plate cylinders.

The plate cylinders of ordinary rotary newspaper printing presses are usually adapted to carry eight plates each, arranged in four sets, each set consisting of two plates 10 extending around the circumference of the cylinder. Each plate is usually the size of a newspaper page, and is semi-cylindrical to fit the cylinder and has its curved edges beveled. The beveled edges of the plates are 15 engaged by clamps connected with the plate cylinder, such clamps having their plate engaging edges beveled or undercut on the same angle as the beveled edges of the plates, but in the opposite direction. The 20 plates must be held firmly to the cylinder, not only to resist the action of centrifugal force as the cylinders revolve at high speed, but to resist displacement when subjected to the printing pressure; and it is very desirable 25 that the plate clamping devices should be such as will enable the operator to fasten or unfasten the plates in the shortest possible time.

Heretofore such plate cylinders have been 30 each provided with a central fixed clamp ring with which the inner edges of the innermost plates are engaged when the plates are properly placed on the cylinder, and the outer edge of each inner plate is engaged by 35 adjustable so-called center plate clamps, which latter clamps are also engaged by the inner edges of the outer plates; and plate clamps are provided at the outer ends of the cylinder to engage the outer edges of the 40 outer plates, and when the plates are placed on the cylinder the outermost clamps are moved inward to engage the outer edges of the outer plates and force them to engage the center clamps and push them inward 45 into engagement with the outer edge of the inner plate, and move it inward until the inner edge of the inner plate is engaged by the fixed clamp ring. To remove the plates it is necessary to first back off the 50 outer clamps to release the outer plate, then remove the outer plate, then back off the center clamps to release the inner plate, and then remove the inner plate. In some cases where it is not desired to use the outer

plates, means have to be provided to engage the inner plates independently of or in connection with the means for engaging the outer plates.

Various constructions of plate clamping devices have been heretofore patented or used, and have been found more or less objectionable in practice; and the principal object of my invention is to provide stiff, rigid outer or master plate clamp, which can be operated rapidly, both to lock the outer and inner printing plates on the cylinder, and to unlock them preparatory to their removal. Another object is to provide for locking the inner plate when the outside plate is not needed. Another object 70 is to facilitate the removal of the inner plates.

In the accompanying drawings I have illustrated one practical embodiment of my invention and will explain the same with reference thereto to enable others to adopt and use the invention; and I refer to the claims for summaries of the novel features of construction and novel combinations of parts for which protection is desired. 80

In said drawings:

Figure 1 is a side view of one half of an ordinary rotary press plate cylinder, equipped with my novel plate clamping devices. 85

Figure 2 is an enlarged detail section of cylinder and end clamp on the line 2-2, Figure 1.

Figure 3 is an end view of the plate cylinder, which parts broken away. 90

Figure 4 is a cross section of the cylinder on the line 4-4, Figure 5.

Figure 5 is a partial section of a plate cylinder with inner and outer plates locked in position for printing. 95

Figure 6 is a partial section of a plate cylinder showing the inner plate locked without outer plate.

Figure 7 is a view like Figure 5 showing the inner and outer plates unlocked. 100

Figure 8 is an enlarged detail section on the line 8-8, Figure 1.

The plate cylinder 1 is shown as provided with the usual grooves or slots 1^a, and with novel clamps to receive the plates thereon. 105 Only the left hand half of the cylinder is shown in Figure 1, as the right hand half is a duplicate of the left, but reversed. A

beveled or undercut clamp ring 2 is fastened firmly to the cylinder at its center, as usual, and is adapted to hold the inner edges of the inner plates P'. The cylinder is provided with a series of intermediate or center plate clamps 3, arranged in the grooves 1^a about half way between the clamp ring 2 and the adjacent end of the cylinder; usually six center clamps are employed around 10 the cylinder, said clamps being undercut on opposite sides to receive the outer edges of an inner plate P' and the inner edge of the outer plate P. These clamps have bases 3^a which slide in the slots 1^a in the cylinder 1, as usual, the bases 3^a having tongues engaging undercut grooves 1^c in slots 1^a to hold the clamps securely on the cylinder while allowing them to be slid in either direction lengthwise of the cylinder.

20 The cylinder is also provided with outer or master clamps 4 adapted to engage the outer curved edges of the outer plates P. The master clamps are preferably semi-circular, being shown as approximate half 25 rings, each extending nearly half way around the cylinder. To enable the clamps 4 to be made very stiff and rigid the outer end of the cylinder is reduced in diameter as at 1^b, outside of the area on which the plates rest, 30 so that the body portion of each clamp 4 can be made quite thick; as shown in Figure 2. Each clamp 4 is provided on its inner side with an inwardly projecting peripheral flange 4^a, which flange is adapted to project 35 over the periphery of the cylinder and engage the outer edge of an outer plate P. This beveled flange 4^a is necessarily thin, as its projection beyond the cylinder surface must be less than the thickness of the printing plate P. The flange 4^a of the clamp has 40 its inner edge beveled to engage the beveled edge of the plate P (Figure 5); and said flange is so wide that its edge will engage the plate P before the body of the clamp 45 contacts with the shoulder at the inner end of the reduced portion 1^b, when the clamp is moved inward to clamp plates on the cylinder.

50 Each clamp 4 has a central inwardly projecting base portion 4^b under its middle section (see Figures 5-8) projecting into the related slot 1^a, and is provided with side tongues 4^c engaging the slots 1^a in the sides of grooves 1^a to hold it in slidably engagement with the cylinder. The master clamp is also provided with a block 4^d near each end, similar in shape to the portion 4^b and also slidably fitting into the grooves 1^a in the cylinder. These blocks 4^d act as guides and 55 "hold downs" for the end portions of clamp 4.

60 The base portion 4^b of clamp 4 is provided with a threaded bore which is engaged by a screw 5, that is rotatably engaged with a ring plate 5^a suitably fastened to the end of

cylinder 1; and said screw is provided with means, as collars 5^b on opposite sides of the plate 5^a, to prevent endwise movement of the screw; and the outer end of the screw is shaped to be engaged by a wrench or other suitable tool whereby the screw may be turned.

Having the parts as thus far described, and assuming the clamps to be in position shown in Figure 1; and plates P and P' having been placed on the cylinder, as in Figure 7; the screw 5 is rotated to force the clamp 4 inward toward the plates; the flange 4^a first engages the outer edge of the plate P, and then the continued action of screw 5 causes clamp 4 to push outer plate P inward until the inner edge of plate P contacts with the opposed beveled portion of middle clamp 3; then the continued inward movement of plate P causes the inner beveled edge of clamp 3 to engage the outer edge of inner plate P'; and moves plate P' inward until the inner edge of plate P' engages clamp 2, and by further operation of the screw 5 the plate P is forcibly and completely locked between clamp 4 and clamp 3; and plate P' between clamp 3 and clamp 2, the space between the plates P, P' being filled by the center clamp 3; thus by the operation of one screw both plates P and P' are locked. The locking of other like plates on the cylinder is produced by operating the related screws as above described. Four screws 5 and related sets of clamps will suffice to secure all eight plates 100 on the cylinder.

Frequently a full complement of plates is not required. In this case it is usually customary to use a narrow web of paper and to omit printing plates P, and substitute 105 "dummy" plates therefor (i. e., non-printing plates thinner than the plates P but of same length) in order that proper actuation of screw 5 may lock plate P', as above described. Instead of using such "dummy" 110 plates in my invention I employ thrust members or bars 6 between master clamps 4 and center clamps 3. These thrust bars 6 are preferably slidably fitted in the slots 1^a, and have tongues fitting in the undercut grooves 1^c (like clamps 3). The thrust bars 6 are preferably so made that their outer surfaces are flush with the cylinder surface, and will support the under surface of the printing plates P opposite the grooves 1^a and thus 120 prevent the overlying portion of the plates being forced by the impression pressure in printing into the groove.

It is preferable to make the thrust bar 6 in sections, as these can be more easily assembled in the grooves. A preferable form of thrust bar is shown in Figures 5-7, such bar being composed of two end-to-end sections 6^a, 6^b, and a screw 6^c, intermediate parts 6^a and 6^b; which screw enables the total 130

length of the thrust bar to be varied. This enables the thrust bar to be accurately adjusted, to cause the clamps to properly engage the plates; especially if the plates should vary in length or not be accurately finished.

To illustrate, (see Figure 5) the screw 6^c can be adjusted until the total length of the thrust bar (6^a, 6^b and exposed part of screw 6^c) is slightly less than the distance between clamp 3, and clamp 4, thus enabling the entire force exerted by screw 5 upon clamp 4 to be equally expended on the plates P and P'. When only inner plates 15 P' are to be used, the screw 6^c can be adjusted to project farther out of 6^b (as shown in Figure 6) to increase the total length of the thrust bar 6, and consequently decrease the extent of rotation of screw 5 necessary 20 to cause said bar 6 to properly operate clamp 3. With this adjustment the proper actuation of screw 5 will force master clamp 4 against the outer end of the thrust bar, and move it inward against clamp 3, force 25 the clamp 3 against plate P', and lock said plate between clamp 3 and fixed clamp 2. The said adjustment of the length of thrust bar 6 is not absolutely necessary, but is advantageous since by reducing "lost motion" 30 it allows the locking up of plates to be done in less time and with less movement between the parts.

To facilitate the removal of the plates P' from the cylinder, hook bars 7 are provided. 35 The outer end of each hook bar is fastened to a master clamp 4 (see Figures 3 and 8) and extends preferably under thrust bar 6 through a slot which is preferably in the bottom of groove 1^a. The inner end of 40 the hook bar extends slightly beyond the related center clamp 3, and has a hook or projection 7^a on its extremity adapted to engage the inner end of such clamp.

In Figures 5 and 6 the plates P, P' are 45 shown locked on the cylinder and hook bar 7 is inoperative. Actuation of screw 5 in a direction to disengage clamp 4 from plate P will not at first actuate clamp 3; but if such actuation of screw 5 is continued it 50 will withdraw clamp 4 from plate P and also cause hook bar 7^a to engage with the inner end of clamp 3, and disengage such clamp from plate P', as shown in Figure 7; so that then both inner and outer plates 55 can be readily removed.

By reducing the end of the cylinder I am able to make the outer or master clamps 4 thick and substantial, whereas heretofore semi-cylindric clamps have been thin, weak 60 and springy. This construction also enables me to make the plate engaging portion of the master clamp, which must project over the cylinder, thinner than the plate, but yet make it very rigid because of the 65 material thickness of the body of the master

clamp. Another advantageous feature is the thrust bar between the master clamp and the center clip, also having such thrust bar made in sections for convenience in assembling and in adjusting to different 70 lengths of plates or distances between the inner and outer clamps. A further advantage is having the thrust bar slidably fitted in the plate clamp guide slots in the cylinder, and having such thrust bar fill the slots 75 and act to support the portions of the plates over the slots, where they have been heretofore unsupported.

I claim:

1. Plate clamping means for plate cylinders, comprising an outer clamp, an inner clamp, and a thrust member interposed between the outer and inner clamps whereby the inner clamp may be actuated by the outer clamp, said thrust member having its 80 outer surface flush with the surface of the cylinder to assist in supporting a plate.

2. Plate clamping means comprising an outer clamp, an inner clamp, and a thrust member interposed between the outer and 90 inner clamps whereby the inner clamp may be actuated by the outer clamp; and means actuated by the outer clamp to positively release the inner clamp.

3. Plate clamping means comprising an outer clamp, an inner clamp, and a thrust member interposed between the outer and inner clamps whereby the inner clamp may be actuated by the outer clamp; and a hook bar connected with the outer clamp and 100 adapted to release the inner clamp.

4. In combination with a cylinder having a groove, an inner clamp in said groove, an outer clamp, and a thrust member in said groove interposed between the inner and outer clamps, whereby the inner clamp may be actuated by the outer clamp, said thrust member having its outer surface flush with the outer surface of the cylinder to support the plates.

5. In combination with mechanism as set forth in claim 4, a member actuated by the outer clamp adapted to positively release the inner clamp.

6. In combination with mechanism as set forth in claim 4, a hook member connected with the outer clamp and adapted to disengage the inner clamp from the plate.

7. Plate clamping means comprising an outer clamp, an inner clamp, and a sectional 120 adjustable thrust member interposed between the outer and inner clamps whereby the inner clamp may be actuated by the outer clamp.

8. Plate clamping means comprising an 125 outer clamp, an inner clamp, and a sectional adjustable thrust member interposed between the outer and inner clamps whereby the inner clamp may be actuated by the outer clamp; and a hook bar connected with the 130

outer clamp and adapted to release the inner clamp.

9. In combination with a cylinder having a groove, an inner clamp in said groove, an outer clamp, and a sectional adjustable thrust member in said groove interposed between the inner and outer clamps, whereby the inner clamp may be actuated by the outer clamp, said thrust member having its outer surface flush with the outer surface of the cylinder to support the plates.

10. In combination with mechanism as set forth in claim 9, a means actuated by the outer clamp adapted to positively release the inner clamp.

11. In combination with mechanism as set forth in claim 9, a hook member operated by the outer clamp adapted to disengage the inner clamp from the plate.

12. In combination a plate cylinder having a portion adjacent the plate supporting area substantially reduced in diameter, a parti-cylindric clamp body slidably mounted upon said reduced portion and having a flange on its inner edge of less thickness than the body and adapted to project over and beyond the adjacent edge of the plate supporting area to engage plates thereon, which may vary in size or be shorter than the plate supporting area, and means whereby the clamp body may be moved axially of the cylinder to cause said flange to engage or disengage a plate.

13. In combination a plate cylinder having a portion adjacent the plate supporting area substantially reduced in diameter and provided with a plurality of longitudinal grooves in the plate supporting portion exterior to said reduced portion, a parti-cylindric clamp body slidably mounted upon said reduced portion and having a flange on its inner edge adapted to project over and beyond the adjacent edge of the plate supporting area to engage plates of various sizes thereon, members connected with said clamp and engaging the said grooves in the cylinder, and means whereby the clamp body may be moved axially of the cylinder to cause said flange to engage or disengage a plate.

14. In combination with a cylinder having its end substantially reduced in diameter adjacent the plate supporting area and provided with a plurality of longitudinal grooves in its plate supporting portion exterior to said reduced portion, a parti-cylindric clamp body slidably mounted upon said reduced end of the cylinder and having a

clamping flange on its inner edge extending longitudinally of the body and adapted to project over the adjacent edge of the plate supporting area of the cylinder to engage a plate thereon; members connected with said body and engaging the said grooves in the cylinder; and a screw operatively connected with the body and the cylinder, whereby the body may be moved axially of the cylinder to cause said flange to engage or disengage a plate.

15. In combination, a plate cylinder having a plate supporting area appreciably longer than a printing plate, and a portion at the outer end of said area substantially reduced in diameter, a curved clamp member mounted on said reduced portion and provided on its inner edge with a curved flange thinner than the plate, and adapted to project over the said area to engage the edges of plates of varying length without contact of the body of the clamp member with the end of the said plate supporting area.

16. In combination, a plate cylinder having a plate supporting area, and a reduced portion at the outer end of said area, a curved clamp member mounted on said reduced portion and provided on its inner edge with a curved flange thinner than the plate, the inner surface of said flange having approximately the same radius as the surface of the plate supporting area of the cylinder, said flange being adapted to project over the said area to engage the edge of a plate without contact of the body of the clamp member with the end of the said plate supporting area of the cylinder.

17. In combination a plate cylinder having a plate supporting surface appreciably longer than the printing plate and a reduced portion at the end, a curved clamp member mounted on the reduced portion of the cylinder provided with a curved flange, said flange being thinner than the plate and rectangular in section except the plate engaging end, such end being beveled, the inner surface of said flange having approximately the same radius as the surface of the plate cylinder and adapted to project axially over the same to enable the beveled edge to engage the edge of the plate without contact of the thicker member of the clamp with the end of the said portion of the cylinder.

In testimony that I claim the foregoing as my own, I affix my signature.

HENRY F. BECHMAN.
